UNITED STATES PATENT OFFICE.

EDWIN A. HART, OF WIRETON, AND ROBERT H. WALLACE, OF NEW BRIGHTON,
PENNSYLVANIA, ASSIGNORS OF ONE-THIRD TO CLARENCE D. BEEMER, OF
BEAVER, PENNSYLVANIA.

FLOOR CONSTRUCTION.

1,116,421.

Specification of Letters Patent. Patented Nov. 10, 1914.

Application filed March 21, 1914. Serial No. 826,437.

To all whom it may concern:

Be it known that we, EDWIN A. HART and ROBERT H. WALLACE, citizens of the United States, residing at Wireton and New Brighton, respectively, in the counties of Allegheny and Beaver, respectively, and State of Pennsylvania, have invented new and useful Improvements in Floor Construction, of which the following is a specification.

10 The present invention relates to improvements in floor construction, the object being to provide a railroad crossing, bridge decking, store rooms, freight houses and the like with a floor formed from slabs made up of 15 reinforced plastic material sufficiently strong to withstand the pressure of heavy weights deposited thereon, the said slabs having interlocking edges to insure the proper arrangement of the same, as well as having 20 their corners beveled and their bodies upon their upper faces formed with a longitudinal registering channel or depression whereby a firm foot hold may be obtained and 25 danger of slipping of draft animals passing over the floor or the vehicles to which the draft animals are attached, will be entirely obviated.

With the above and other objects in view which will appear as the nature of the invention is more fully understood the improvement resides in the construction, combination and arrangement of parts set forth in the following specification and falling within the scope of the appended claims.

35 In the drawings accompanying this specification there has been illustrated a satisfactory reduction of our improvement to practice, and in which:

Figure 1 is a plan view of our flooring or 40 decking arranged between the rails at a railway crossing, Fig. 2 is a sectional view on the line 2—2 of Fig. 1, Fig. 3 is a similar sectional view on the line 3—3 of Fig. 1, Fig. 4 is a section on the line 4—4 of Fig. 1, Fig. 5 is a detail perspective view of one of 45 the end slabs, Fig. 6 is a similar view of one of the slabs provided with a nose or flange which is adapted to be received within the fishing space to one side of a rail, and Fig. 7 50 is a horizontal sectional view through the slab illustrated in Fig. 6.

In the drawings, the improvement is illustrated in applied position upon a railway crossing, but, as previously stated, the de-

vice is not to be thus restricted in its useful 55 employment, and in the said drawings the numerals 1 designate the rails at the crossing, and 2 the crossing proper which is provided with ties or sleepers 3 that are of course, arranged transversely beneath and 60 support the rails 1. The decking or floor for the crossing is broadly indicated by the numeral 4, and comprises a plurality of substantially rectangular slabs 5 and 6, the slabs 6 being of a less length than the slabs 5, and 65 in the showing in the drawing one of the slabs 5 arranged against one of the slabs 6 have their combined length equal to the width of the crossing. This arrangement, however, is not essential, as the crossing 70 may be of any desired width, but certain of the shorter slabs 6 are necessarily arranged at the ends of the crossing. The end slabs, in the showing of the drawings, have one of their ends rounded to provide an integrally 75 formed coping which is indicated by the numeral 7, and each of the said slabs has its upper longitudinal edge beveled or inclined downwardly from its upper face to its sides, as indicated by the numeral 8, so that when 80 the sides of the slabs are brought into abutting position, the beveled corners will provide a continuous V-shaped groove, the said groove serving as an anti-slipping means for 85 pedestrians as well as for animals and vehicles traversing the crossing. The slabs 5 and 6 are further provided with centrally arranged longitudinally extending V-shaped grooves 9 which serve a similar purpose to that of the beveled corners 8, and the slabs 90 are further provided with openings 10 which are arranged within the grooves 9 and which are spaced from each other a distance equaling the distance between the center of the adjacent sleepers 3, the said openings being adapted to receive lag screws 11 which are forced therethrough to within the sleepers 3, and which retain the sleepers in proper position upon the crossing. The 95 slabs are so arranged as to have their contacting ends meet centrally of the sleepers, but the joints thus provided are broken or in other words, the meeting end of one slab is not arranged upon the said slab with the meeting end of the adjacent or coengaging 100 slab and the meeting ends of the said slabs are provided with vertically disposed substantially semi-cylindrical depressions 105

which, when the slabs are brought together form round openings similar to the openings 10 and through which lag screws similar to the lag screws 11 pass and enter the 5 sleepers below the joints of the slabs.

One of the slabs has, what we will term, its inner end formed with a transverse slot or depression 13 within which the tongue 12 is positioned, and in the construction illustrated in the drawings, it is necessary that 10 one series of the slabs which are arranged adjacent the inner faces of the rails 1 contact with the said rails in order to provide a complete flooring for the crossing and therefore 15 these slabs which may be indicated by the numerals 14, have their upper corners adjacent the rails grooved longitudinally to provide the lower corners of the said slabs with longitudinal extensions or flanges 15, 20 and the said flanges are provided with metallic reinforcements 16 which are of a serpentine formation, being bent in zigzag directions throughout their length. All of the sleepers are provided with spaced metallic 25 reinforcing bars 17 which are so positioned to impart the desired amount of rigidity and strength to the slabs.

In order to lessen the weight of the sleepers, as well as to provide for a certain 30 amount of flexibility, which is permitted by the particular arrangement of the metallic reinforcing members, the underface of the slabs is channeled transversely, as at 18, the upper walls provided by the channels terminating just below the lower reinforcing 35 bars 17, and the channels are of a width equaling the distance between the sleepers of each pair of sleepers 3.

The slabs providing the flooring may be, 40 it will be noted, easily and quickly applied and easily removed should any of the slabs become worn or broken, it being understood that the heads of the lag screws being arranged within the V-shaped grooves permit 45 of the application of a suitable instrument for the withdrawal of the said screws.

Having thus described the invention, what we claim is:

1. A flooring made up of slabs each embodying a reinforced plastic member having 50 its corners beveled toward its side, the end of one of the slabs being formed with a transverse tongue, the end of the co-acting slab being formed with a transverse groove 55 adapted to receive the tongue, and the upper

face of each of the slabs being provided with a centrally disposed longitudinally extending V-shaped groove.

2. A flooring made up of reinforced plastic slabs, sleepers for supporting the 60 slabs, each of the sleepers having its upper corners beveled toward its sides, the co-acting slabs being of different lengths and having interlocking ends, each of the slabs being each provided with a central longitudinally extending V-shaped depression 65 upon its upper face, the slabs being formed with openings which communicate with their grooves and which are arranged intermediate of the sleepers, and lag screws passing through the openings to within the sleepers. 70

3. A railroad crossing having a flooring made up of metallic reinforced plastic sleepers, each of said sleepers comprising a substantially rectangular member having its upper corners beveled toward its sides, its center, upon its upper face, formed with a longitudinally extending V-shaped groove, the end sleepers of the crossing having their 80 ends curved downwardly to provide a coping, the sleepers having their meeting ends formed with a tongue and groove connection, the slabs adjacent the inner faces of the rails of the crossing having their corners opposite the said rails channeled longitudinally to provide a lower flange, a serpentine metallic reinforcement for each of said flanges, the meeting ends of all of the slabs being arranged over the said sleepers upon 85 which the rails and slabs are supported, the joints of each of the series of slabs being broken, the underfaces of each of the slabs being channeled transversely a distance equaling the distance between the opposite 90 sides of the sleepers, the said sleepers being formed with openings at their meeting ends and at their remaining portions which rest directly upon the sleepers, the said openings passing from the central V-shaped grooves 95 through the slabs, and lag screws passing through the opening into the sleepers. 100

In testimony whereof we affix our signatures in presence of two witnesses.
